UNITED STATES PATENT OFFICE

EMMIT G. LATTA, OF FRIENDSHIP, NEW YORK, ASSIGNOR OF ONE-HALF
TO ADRIAN C. LATTA, OF SAME PLACE.

VELOCIPED.

SPECIFICATION forming part of Letters Patent No. 323,695, dated August 4, 1885.

Application filed March 10, 1885. (No model.)

To all whom it may concern:

Be it known that I, EMMIT G. LATTA, of Friendship, in the county of Allegany and State of New York, have invented new and useful Improvements in Velocipedes, of which the following is a specification.

This invention relates to an improvement in that class of bicycles known as "safety bicycles," in which the cranks are arranged below the center of the driving-wheel and connected to said wheel by endless chains and sprocket-wheels, and more particularly to bicycles of this class in which the driving mechanism is adjustable forwardly or backwardly, for adjusting the machine for greater safety or for greater power, as may be desired.

The object of the present invention is to improve the construction of the adjustable driving mechanism in such manner that the desired adjustment can be effected instantly without stopping the machine or dismounting, and to increase the rigidity of the machine; and my invention consists to these ends of the improvements which will be hereinafter fully set forth, and pointed out in the claims.

In the accompanying drawings, consisting of two sheets, Figure 1 is a side elevation of a bicycle provided with my improvements. Fig. 2 is a cross-section on an enlarged scale in line *x x*, Fig. 1. Fig. 3 is a cross-section on an enlarged scale of the adjusting device on one side of the driving-wheel in line *y y*, Fig. 1. Fig. 4 is a cross-section on an enlarged scale in line *z z*, Fig. 1. Fig. 5 is a cross-section on an enlarged scale in line *x x*, Fig. 3. Fig. 6 is a fragmentary longitudinal section of the jointed brace. Fig. 7 is a fragmentary sectional elevation of the driving mechanism with the driving-wheel adjusted rearwardly. Figs. 8 and 9 are fragmentary side elevations showing modified constructions of the adjusting devices.

Like letters of reference refer to like parts in the several figures.

A represents the driving-wheel, *a* the hub thereof provided with chain or sprocket-wheels *a' a'*, and an axle, *a²*, rigidly secured to the hub *a*.

B represents the fork, B' the backbone, and B² the rear wheel.

C is an adjustable arm pivoted to the lower bent end *b* of each part of the fork B by a pivot-bolt, *e*, and provided above the lower end of the fork with suitable bearings, *c'*, in which the axle *a²* turns. These bearings may be of any approved construction, and are shown as plain bearings in the drawings to simplify the same. The arms C are preferably provided with a series of openings, *c'*, in either of which the bolt *e* can be placed, whereby the fork B can be raised or lowered on the arms C, if desired, and the lower bent portion of the fork is preferably provided with a series of openings, *b'*, in either of which the pivot-bolt *e* may be placed and whereby the arms C can be raised and lowered on the fork, if desired.

D D represent the driving-chain or sprocket-wheels arranged below the center of the driving-wheel and supported on the adjustable arms C.

d represents the endless chains which run around the wheels D D and *a'*, and communicate motion from the former to the latter.

d' represents the cranks secured to the outer ends of short shafts *e*, to the inner ends of which the crank-wheels D are secured. The shafts *e* are supported between the cranks and the crank-wheels in bearings *e'*, which are adjustably secured to the arms C by clamps or loops F, which embrace the arms C, and are movable on the same, and secured in position by set-screws *f* after being adjusted for tightening the chains.

g represents the pedals attached to the cranks D. The arms C are preferably bent inwardly between the two portions of each driving-chain to clear the screw-nuts whereby the pedals are secured to the cranks.

H is a jointed brace arranged on each side of the driving-wheel, and connected at one end with a sleeve or clamp, I, which is secured to the fork B, and pivoted at its other end to a bifurcated lug, J, which is formed on the upper end of the adjustable arm C above the bearing *c'* of the driving-wheel. The braces H, on both sides of the driving-wheel, operate in the manner of toggle-joints, and serve to hold the arms C and the driving mechanism supported thereon in either of two positions, and

permit the position of the driving-wheel to be changed at the will of the rider. The jointed braces H consist each of the following parts: h is an arm pivoted with its rear end to the 5 clamp I, and provided on its front side with a forwardly-projecting stem, h', which is surrounded by a cushion, h², formed of rubber or of a suitable metallic spring. h' is a link, provided on its rear side with an opening, h³, in 10 which the stem h' slides, and pivoted with its front end to a foot-lever, K, which is pivoted in the bifurcated lug J of the arm C. The arm h and the link h³ are provided on their adjacent sides with flanges, between which 15 the spring h² is seated.

In the position of the parts represented in Figs. 1, 3, and 6, the foot-lever K, link h³, and arm h stand in a straight line, or nearly so, and hold the driving-wheel at its greatest distance 20 in front of the fork and of the rider's seat. In this position of the parts the machine is best adapted to descend sharp grades or pass over rough ground. When the rider desires to adjust the machine for use on ordinary 25 good roads, he raises the front ends of the foot-levers K by placing his feet under the foot-rests k of the foot-levers, whereby the rear ends of the levers K are depressed, carrying with them the front ends of the links h³, and 30 changing the parts to the position represented in Fig. 7. In effecting this change of position the links h³ turn with the arms h, and the parts come to rest when the front end of the link h³ strikes the rear side of the lug 35 J. In this position of the parts the driving-wheel is nearer the fork and more directly under the rider's seat than in the position represented in Fig. 1, and the crank-wheels D have been moved forwardly by the turning 40 movement of the arms C on their pivots, and are now more directly under the center of the driving-wheel. In order to return the parts to the position represented in Fig. 1, it is only necessary to press down the front ends of the 45 levers K by placing the feet upon the foot-rests k. The downward movement of the front ends of the levers K is limited by the lugs J, and when the levers K are arrested by the lugs J the bolts which connect the levers 50 with the links h³, are slightly above a line drawn through the points at which the levers K and arms h are pivoted, so that the weight of the rider will tend to hold the parts in this position. In either position of the driving- 55 wheel a great part of the weight of the rider rests upon the spring h², and when the wheel strikes an obstruction, the spring, lying almost in a direct line between the part of the wheel which strikes and the rider, relieves the 60 cushion and avoids considerable vibrations of the machine.

In the position of the parts represented in Fig. 1, the crank-wheels are arranged well back under the rider, which affords a greater 65 leverage to prevent a forward fall should he back-pedal in going down hill, and enables the

rider to lean forward on his seat and stand erect on the pedals in mounting a steep hill, which is more comfortable, and enables him to apply his weight to better advantage than is 70 possible with the cranks in their forward position.

By raising the clamps I on the fork, or changing the position of the pivot-bolt c so that the foot-levers K and link h³ will not 75 quite straighten out when the foot-levers are depressed, the driving-wheel will only remain in its forward position so long as the foot-levers are depressed, and upon releasing the foot-levers the parts return to the position represented in Fig. 6 by the weight of the rider. Such an adjustment of the parts is desirable 80 when the cranks are set well back in their forward position and the rider wishes additional safety in coasting.

The rear ends of the arms C are bent upwardly, and connected by a bow, L, which extends around the rear part of the driving-wheel. This bow L stiffens the arms C against torsional and lateral movements, and enables 90 them to be made lighter, and causes both arms to move simultaneously on their pivots. The loop L is curved or inclined upwardly, as represented in Fig. 1, to enable the machine to pass over obstructions without causing the 95 loop to come in contact therewith. The bow may be formed in one piece, with the arms C C, as represented in the drawings; or it may be a separate piece, permanently or removably attached to the arms.

l represents a step secured to the bow L on one side of the driving-wheel A. The step l is formed with an adjustable clamp, l', which embraces the bar of the bow L, to which it is secured by a tightening-screw, l'', so that the 105 step can be attached to the bow in the most convenient position.

The front ends of the foot-levers K may be connected by a similar bow extending around the front portions of the driving-wheel, if desired, whereby both levers can be operated with one foot and the rigidity of the machine will be somewhat increased.

The jointed braces H will operate in the manner described by omitting the parts of the 115 levers K which extend forwardly from their pivots; but in that case the adjustment cannot be effected without dismounting.

In the modified construction represented in Fig. 8 the arms C C and bow L form a downward and rearward continuation of the fork-arms B, and the driving-wheel is journaled in arms m, which are pivoted to the arms C, and adjusted by the jointed braces H in the same manner that the arms C are adjusted in the 125 construction previously described.

In the construction represented in Fig. 8 the crank-wheels are not adjusted when the driving-wheel is adjusted, while in the construction previously described both the driving-wheel and the crank-wheels are adjusted simultaneously. Each of the arms m is pro-

vided with a series of holes, in either of which the pivot-bolt m' can be placed, whereby the driving-wheel can be raised in the fork for good roads or be lowered for muddy roads.

5 Upon adjusting the driving-wheel the crank-wheels are adjusted on the arms C by means of the sliding clamp F. The arms m, on opposite sides of the driving-wheel, may be connected by a bow extending around the upper portion of the wheel in convenient reach of the rider's hand. The pivot-bolt m' is arranged midway between the forward and backward positions of the driving-wheel on a line drawn through the center of the crank-wheel, and in changing the position of the wheel the slack of the driving-chain permits the arm to turn over on its pivot, when the chain will run again as freely as before.

In the construction represented in Fig. 9 the driving-wheel is journaled in the fork-arms B, and the crank-wheels D only are made adjustable by means of the jointed braces H, which are in this case attached to the arms C below the center of the driving-wheel, and to extensions n of the fork-arms B, which project below the center of the driving-wheel.

The adjustable support for the driving-wheel may be applied to bicycles which have not the endless-chain driving-gear for the purpose of moving the driving-wheel forwardly to a position of greater safety in descending hills, or backwardly under the rider in mounting hills.

I claim as my invention—

1. The combination, with the driving-wheel and fork-arms, of pivoted supporting-arms, and a toggle-joint whereby the supporting-arms are locked in position, substantially as set forth.

2. The combination, with the driving-wheel, fork-arms, and crank-wheels, of pivoted arms supporting the driving-wheels and crank-wheels, and a toggle-joint whereby the pivoted supporting-arms are locked in position, substantially as set forth.

45 3. The combination, with the driving-wheel and fork-arms, of the pivoted supporting-arms, the jointed locking-brace H, and the foot-lever K, substantially as set forth.

4. The combination, with the driving-wheel and fork-arms, of the pivoted supporting-arms, and a jointed locking-brace, H, composed of

the arm h and link h' , capable of a sliding movement on each other, substantially as set forth.

5. The combination, with the driving-wheel and fork-arms, of the pivoted supporting-arms, and a jointed brace, H, composed of the arm h, provided with a stem, h' , and the link h'' , capable of sliding on said stem, substantially as set forth.

60 6. The combination, with the driving-wheel and fork, of the pivoted arms supporting the wheel, and a spring interposed between the wheel and the fork, whereby the vibrations are reduced, substantially as set forth.

65 7. The combination, with the driving-wheel and fork-arms, of pivoted supporting-arms, and a locking toggle-joint provided with a spring or cushion, substantially as set forth.

70 8. The combination, with the driving-wheel and fork-arms, of the pivoted supporting-arms, and a jointed brace, H, composed of the arm h and link h' , provided with an interposed spring, h'' , substantially as set forth.

75 9. The combination, with the driving-wheel and fork-arms, of the pivoted arms C, provided with upward extensions J, levers K, pivoted to said extensions, and the jointed braces H, connecting the levers K with the fork-arms, substantially as set forth.

80 10. The combination, with the driving-wheel and fork arms, of the pivoted arms C, provided with upward extensions J, levers K, pivoted to said extensions, the jointed braces H, attached to said levers, and the adjustable clamps I, connecting the braces H to the fork-arms, substantially as set forth.

85 11. The combination, with the fork, of supporting-arms C, having their outer ends connected by a stiffening-bow extending around the rim of the wheel, pivot-bolts connecting the arms C with the fork, a driving-wheel provided with sprocket-wheels a' , and crank-wheels D, journaled in the arms C, and fastenings whereby the arms C are adjustably attached to the fork, substantially as set forth.

90 Witness my hand this 5th day of March, 1885.

EMMIT G. LATTA.
